CLAIM

I claim the ornamental design for a truck blinker light ornamental frame, as shown.

DESCRIPTION

FIG. 1 of the drawings is a perspective view showing the front, top, and left side of a truck blinker light ornamental frame embodying the design of my invention;

FIG. 2 is a side elevation view of the left side of the ornamental frame;

FIG. 3 is a front elevation view;

FIG. 4 is a top plan view;

FIG. 5 is a back elevation view;

FIG. 6 is a side elevation view of the right side;

FIG. 7 is a bottom plan view; and,

FIG. 8 is a reduced-in-size perspective view of the ornamental frame showing a portion of its usual environment that is not part of my design in phantom lines, including the left headlight assembly and left front fender of a truck.
